(57) **CLAIM**

I claim the ornamental design for a bypass fuel pressure regulator, as shown and described.

DESCRIPTION

FIG. 1 is a front perspective view of a bypass fuel pressure regulator showing my new design.

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate environmental structure on the article and form no part of the claimed design. The broken lines immediately within the perimeters of the openings to the interiors in FIGS. 6 and 7 depict boundaries of the claimed design. The boundaries and surfaces visible within them in these views form no part of the claimed design.
